UNITED STATES PATENT OFFICE.

FRANK MALOCSAY, OF NEW YORK, N. Y., ASSIGNOR TO SONORA PHONOGRAPH CORPORATION, A CORPORATION OF NEW YORK.

TONE-ARM FOR TALKING-MACHINES.

1,276,551.

Specification of Letters Patent. Patented Aug. 20, 1918.

Application filed February 11, 1916. Serial No. 77,690.

To all whom it may concern:

Be it known that I, FRANK MALOCSAY, a citizen of the United States, residing in the borough of the Bronx, county of Bronx, city 5 and State of New York, have invented a certain new and useful Tone-Arm for Talking-Machines, of which the following is a specification.

My invention relates to a tone-arm for 10 talking machines of the disk record type, and has for its object, to produce a tone-arm which is simple and cheap, and one which may be moved to the position wherein the stylus will engage with the record groove 15 and be locked in such position.

A further object is to produce a tone-arm which may be swung to one side of and above the record surface and be locked in such position.

20 A further object is to so proportion the parts that the tone-arm cannot be removed from its position relatively to the rest of the apparatus until it shall have been swung horizontally to a predetermined position.

25 These and further objects will more fully appear in the following specification and accompanying drawings considered together or separately.

I have illustrated my invention in the following drawings, in which Figure 1 is a top plan view of a portion of the talking machine embodying my invention;

Fig. 2 is a side elevation of the same partly in section;

Fig. 3 is a similar view with the tone-arm in another position;

Fig. 4 is a detail plan view of locking spring;

Fig. 5 is a section on the line 5—5 of Fig. 2; and

Fig. 6 is a detail sectional view of a modified form of bearing for the tone-arm.

In all of the above views like parts in all the figures are designated by similar reference characters.

In the drawings 1 designates a support which is the usual partition for separating the motor and horn compartment from the turn-table compartment of a talking machine cabinet. Through the support 1 ex-

tends a shaft 2 from a suitable motor (not shown). The shaft 2 carries a turn-table 3 on which is supported a disk record 3'.

At one side of the turn-table 3 and usually in one corner of the cabinet is a collar 4 which forms the upper extensions of a horn (not shown). In the lower end of the collar is a notch 7. Mounted within the collar 4 is a sleeve 5. The sleeve is provided at its upper end with a notch 6, for a purpose to be hereafter described.

Loosely mounted in the upper part of the collar is a hollow tone-arm 8. This tone-arm is of the usual step-down variety and carries at its free end a reproducer 9. The end of 65 the tone-arm which enters the collar is reduced in diameter and carries a ring 10, the exterior surface of which is curved and forms a zone of a sphere the center of which is at the center of the reduced tubular portion of the tone-arm. At diametrically opposite sides of the ring 10 is a bayonet joint slot 11 and engaging the slot at diametrically opposite sides of the extension of the tone-arm is a trunnion 12.

The lower extremity of the tone-arm is provided with a wedge shaped finger 13, which engages with a wedge shaped track 14 on a lever 15 which is pivoted at 16 to the under side of the support 1. The track 14 is 80 provided with two angular surfaces. When the finger engages the inclined surface to the left as in Fig. 2 the tone-arm is locked in operative position as regards the situation relatively to the plane of the record and 85 when the finger engages the right hand side of the track as in Fig. 3 the tone-arm will be locked in position above the turn-table and the record may be moved. Beyond the pivot 16 a spring 17 is employed to hold the track 90 14 in engagement with the finger 13.

In Fig. 6 is shown a modification wherein is provided a ball bearing for the tone-arm. The trunnions 12 project from the spherical surface of the ring 10 and pass through 95 openings in a collar 5', and into angle slots 11', in a ring 21. A ball race 18 is formed in the exterior surface of the collar 5', and a range of balls 19 is disposed therein. A ring 20 is carried in the collar 4, and supports the 100

balls. The ring 21 is in intimate engagement with the collar 4 and detains the balls in place.

The tone-arm is pivoted by the engagement of the trunnions with the horizontal extensions of the angle slots, the collar 5' may rotate in a horizontal plane on the balls, and at the same time permits the tone-arm to pivot relatively to the collar.

10 The operation of my improved tone-arm is as follows:

With the arm in the position shown in full lines in Figs. 1 and 2, the stylus of the reproducer is free to travel across the record 15 surface of the disk from the edge to the center or vice versa. During that travel the tone-arm, owing to the length of the horizontal slot of the bayonet joint, is locked against removal from the collar, and locked 20 in position parallel to the record in which the stylus is in engagement with the record groove by the engagement of the finger 13 with the outer face of the track 14.

When it is desired to remove the disk 25 from the turn-table, the tone-arm is swung upward on the trunnions until the finger 13 has depressed the lever 15, and become seated on the rear face of the track 14. The tone-arm will now be locked in the position 30 shown in Fig. 3. The notch 6 in the sleeve 5 will permit the rear portion of the tone-arm 8 to swing down below the top of the collar 4, and the spherical surface of the ring 10 will permit the swinging of the tone- 35 arm 8 while still making a close fit with the bore of the sleeve 5, and prevent escape of the sound.

After the tone-arm has been raised it may be swung laterally to the position shown in 40 broken lines in Fig. 1, so as to be clear of the turn-table and facilitate the removal of the record disk. While in this position the arm is locked to the sleeve by the engagement of the trunnions with the horizontal 45 portions of the bayonet joints.

When it is desired to remove the tone-arm from the collar, it is swung to a position opposite to that shown in broken lines in Fig. 1, until the trunnions 12 come under the vertical grooves in the bayonet joint when the tone-arm may be raised from the collar.

In accordance with the provisions of the patent statutes, I have described the principle of my invention, together with the apparatus which I now consider to represent the best embodiment thereof, but I desire to have it understood that the apparatus shown is merely illustrative, and that the invention may be carried out in other ways.

Having now described my invention, what I claim as new and desire to secure by Letters Patent, is as follows:

1. In a talking machine, having a tone-arm, and a spherical surface thereon, diametrically disposed trunnions on the spherical surface, a collar surrounding the spherical surface, there being openings in the collar to receive the trunnions, a ball race in the collar, and balls therein, a ring, surrounding the collar and supporting the balls, a second ring engaging the balls, there being angle slots in the last mentioned ring for engagement with the trunnions, and a support for the rings. 65

2. In a talking machine, the combination with a tone-arm, a wedge shaped finger at the lower extremity of the tone-arm, and a collar, the tone-arm engaging within the collar, a latch below and secured to the motor board and means for supporting the same, said latch having a double faced, arc-shaped track, said track engaging the finger to lock the tone-arm in any one of a plurality of positions. 75

3. In a talking machine, the combination with a tone-arm, and a spherical surface on the tone-arm, of a collar, a support for the same, there being an angle slot in the collar, a trunnion on the tone-arm engaging the slot, whereby the tone-arm may rotate on a plane parallel to the axis of the collar, a finger on the lower extremity of the tone-arm, of a spring actuated lever, a support for the lever, said lever having a track engaging either side of the finger for locking the tone-arm in a raised or lowered position, said head being arc shaped to permit movement of the tone-arm, while locked, in a horizontal plane. 85

4. In a talking machine, the combination with a tone-arm capable of vertical and horizontal swinging movements, a reduced portion on the lower end of said tone-arm, a wedge-shaped finger on the extremity of such reduced portion of the tone-arm, of a spring actuated lever pivoted to the motor board, a support for the lever on the motor board, said lever having an elongated, arc-shaped track engaging either side of the finger for locking the tone-arm in a raised or lowered position, irrespective of the horizontal position of the tone-arm. 105

This specification signed and witnessed this 5th day of February, 1916.

FRANK MALOCSAY.
